UNITED STATES PATENT OFFICE

FRITZ EBERT, OF OBERNDORF-ON-THE-NECKAR, GERMANY

CHAIN STITCH SEWING MACHINE OF THE ZIGZAG TYPE

Application filed January 17, 1930, Serial No. 421,540, and in Germany January 16, 1929.

The present invention relates to a chain stitch sewing machine of the zigzag type. In sewing machines of this class the needle and the looper are continually adjusted to and fro laterally during sewing to insure both the proper forming of the stitches and the production of a seam running in true zigzag fashion. Moreover, to keep the needle and the looper constantly in correct working position relative to one another, additional motion is imparted to the looper by a joint swinging about the needle lever so that the stitch-forming members always cooperate in the same position notwithstanding their lateral displacement. The devices hitherto employed to attain this end are comparatively complex and require numerous as well as unsuitable transmission and control members not desirable in high speed machines as vibration of the moving parts is caused thereby.

Compared with the present state of the art the invention is distinguished chiefly by simplicity of design, i. e., by the small number of parts used, which results in increased working speed without reduction in safety or, in other words, in greater output while facilitating also the production of the device.

According to the invention, these advantages are attained by causing the cam groove displacing the needle and the looper laterally in the known manner to adjust the looper by means of a double-armed lever positioned at the needle-lever.

The invention is illustrated by way of example in the accompanying drawing, in which Figure 1 is a front view of the sewing machine; Fig. 2, a top view thereof; Fig. 3, a section of the looper drive; Fig. 4, a sectional side view of the driving end of the machine; and Figs. 5 and 6 are, respectively, a top and side view of the device adjusting the looper laterally.

The sewing machine according to the invention is operated in the manner usual for chain stitch machines of the zigzag type, that is, the stitch-forming members such as the needle 1 and the looper 2 are continually displaced laterally to and fro during the sewing step. The drive of the stitch-forming mem-

bers 1, 2 is of known type and not described in detail.

The lateral displacement of the needle 1 and looper 2 is brought about by a cam groove 3 already known to serve for this purpose and disposed laterally on a spur gear 4 rotated continually by means of the driving shaft 5 and the pinion 6.

The groove 3 is engaged by the roll 8 of a bell crank 7, the roll oscillating about a fixed pin 9 and the bell crank moving the needle bar frame 10 continually to and fro laterally during sewing by means of the joint 11.

Simultaneously, the looper 2 is displaced laterally also by the cam groove 3 or the bell crank 7 which has a rearwardly projecting arm 12 connected with a ball joint 13 which in turn is articulated to a lever 14. The lever 14 is positioned in the rear on a cross shaft 15 carrying in front a second lever 16 which is pivotally connected by a joint 17 to a bell crank 18 or the like which can be moved about a pin 19 and is connected with the lower end 20 of the usual needle lever 21. Moreover, by means of a spherical connection 22 it is in communication with the connecting rod 23 of the looper 2 so that the latter, together with the needle 1, produces the seam in the known manner and both are simultaneously displaced laterally by the cam groove 3, the working positions of the needle 1 and looper 2 relative to one another being always the same.

I claim:

A chain stitch sewing machine of the zigzag type, having a cam for displacing the needle and looper laterally during operation, comprising in combination a double-armed needle lever, one of the arms of said needle lever being relatively long and extending downwardly, the fulcrum pivot of the needle lever being near the top of said arm, means to oscillate said needle lever, a drive cam, means actuated by said cam to cause lateral displacement of the needle, a second lever having two arms extending upwardly and having its fulcrum pivot carried by the lower end of the depending arm of the needle lever, a looper, a connecting rod for the same, one end of said connecting rod being pivotally

connected to one end of said second lever, and means actuated by the cam and operating the other end of said second lever, whereby the said second lever is oscillated with respect to the needle lever while simultaneously the needle lever itself oscillates the fulcrum of the said second lever.

In testimony whereof I affix my signature.
FRITZ EBERT.
